Primary Examiner — Susan Bennett Hattan*Assistant Examiner* — Rashida C McCoy(74) Attorney, Agent, or Firm — Knobbe Martens Olson & Bear, LLP(57) CLAIM

I claim the ornamental design for a removable neoprene sleeve for an airport beverage dispenser, as shown and described.

DESCRIPTION

FIG. 1 is a perspective view of a removable neoprene sleeve for an airport beverage dispenser showing my new design with the sleeve mounted on the airport beverage dispenser shown in broken lines;

FIG. 2 is a front view thereof;

FIG. 3 is a rear view thereof;

FIG. 4 is a left side view thereof;

FIG. 5 is a right side view thereof; and,

FIG. 6 is a top view, the bottom view being a mirror image. The broken lines in the drawings represent unclaimed environmental subject matter and form no part of the claim.
